UNITED STATES PATENT OFFICE.

FRANKLIN S. COOLEY, OF BROOKLINE, MASSACHUSETTS.

CIGAR AND PROCESS OF MAKING SAME.

1,104,779.

Specification of Letters Patent. Patented July 28, 1914.

Application filed July 17, 1913. Serial No. 779,484.

To all whom it may concern:

Be it known that I, FRANKLIN S. COOLEY, a citizen of the United States, residing at Brookline, county of Norfolk, State of Massachusetts, have invented a certain new and useful Improvement in Cigars and Processes of Making Same, of which the following is a specification, reference being had therein to the accompanying drawings.

10 My invention has for its object a new and improved cigar and the process of making the same.

More particularly the object of my invention is a cigar which will burn more slowly than cigars as heretofore made while at the same time burning evenly. To this end I construct the body or filler of the cigar from a plurality of superposed leaves of tobacco which are densified and compressed 20 and have longitudinal corrugations formed therein. When the sheet is rolled into the cigar, the grooves between the ribs form uninterrupted air passages longitudinally of the cigar while the tobacco being compressed 25 and densified tends to burn slowly after the manner of plug tobacco. A wrapper may or may not be used and if used the wrapper may be of leaf tobacco or of paper as desired.

30 In the following specification I have used the term cigar to include any smoking article composed wholly or in part from a bundle of tobacco with or without a wrapper. It therefore includes cigarettes, cigars, cheroots, stogies, and the like.

The invention will be fully understood from the following description taken in connection with the accompanying drawings, and the novel features thereof will be 40 pointed out and clearly defined in the claims at the close of the specification.

In the drawings, Figure 1 is a view in perspective of a cigar embodying my invention. In this figure the proportions of the 45 layers are somewhat exaggerated to make their relations clearer. Fig. 2 is a view in perspective of the sheet of compressed tobacco from which the cigar is formed. Fig. 3 is a view in perspective of a mold for 50 making the corrugated sheet shown in Fig. 2. Fig. 4 shows a cigar embodying my invention but made without a wrapper. Fig. 5 shows a slightly modified form of the

cigar embodying my invention. Fig. 6 shows the die for making the cigar shown in Fig. 5.

Referring to the drawings, in Fig. 3 there is shown a die composed of two members A and B. The upper of these members is corrugated, as shown at a a. A number of 60 parts of leaves of tobacco, properly moistened, are superposed and laid between the dies being arranged to form as nearly as possible a uniform layer of tobacco. The tobacco should be in a moist pliable condition, and the number of sheets to be used will depend upon the particular article to be made, and its size. The tobacco is then subjected to considerable pressure, in the dies, so that it is formed into a sheet of the 70 shape shown in Fig. 2 having corrugations running longitudinally thereof. The pressure not only forms the corrugations in the sheet, but also compresses and densifies the tobacco so that it tends to burn slowly and 75 evenly. The sheet is then rolled. If a wrapper is employed, as is shown at C, its edge c may be folded over the proximate edge of the sheet of compressed tobacco and the cigar is rolled beginning on that side, 80 the other projecting edge d being employed to seal the finishing roll. The finished cigar is shown at D in Fig. 1. In Fig. 4 there is shown at E a cigar similarly constructed but without the employment of any wrapper. 85

In Fig. 6 is shown a die adapted to make corrugations on both sides of an interposed sheet of tobacco. The grooves formed by the die on the under side of the sheet are comparatively small, and are formed by the 90 ribs f on the under die member F. The ribs f are located opposite the grooves g in the upper die member G. In Fig. 5 is shown at H a cigar made by the use of the die shown in Fig. 6. The small grooves and corrugations formed on the back of the sheet make it possible to roll the sheet more easily than when the corrugations are formed only on one side. In this specification I have shown flat dies as the particular means of forming 95 the compressed sheet of tobacco but I do not limit myself to this as any suitable die may be used, as for instance suitable grooved rolls by which a continuous sheet can be formed.

100 It will be seen that the cigar embodying

my present invention has air passages extending throughout its length, said air passages being regularly distributed throughout the cross section of the cigar. These air 5 passages insure the free draft and perfect combustion. The tobacco of which the cigar is composed being compressed and densified burns much more slowly than the tobacco of a cigar constructed in the ordinary 10 manner and also burns more evenly. In this respect the cigar made in accordance with my novel process resembles a bundle of sliced plug tobacco.

In corrugating the sheet forming the body 15 of the cigar and made up of several superposed leaves of tobacco, as herein shown and described, it will be obvious that the sheet or body has closely compressed areas and intervening areas which are relatively loose, 20 so that while the cigar made from the rolled sheet will be slow-burning, owing to the closely compressed areas, there will be sufficient looseness so that it will "draw" properly. The cigar embodying my invention 25 has the additional advantage that little or no skill is required in its manufacture. As is well known, the manufacture of ordinary cigars requires great skill and deftness in the arrangement of the leaves of tobacco 30 and in rolling and finishing the cigar. In the manufacture of my novel cigar skilled labor is not required, as a person unfamiliar with the handling of tobacco can easily superpose the sheets, subject them to pres-

sure in the die and roll up and finish the 35 cigar.

What I claim is:

1. A cigar comprising a body composed of a series of leaves or sheets of tobacco, said body having closely compressed and relatively loose areas, and which body is rolled upon itself to form the cigar. 40

2. A cigar comprising a corrugated body of tobacco composed of a series of leaves or sheets, said body being rolled upon itself 45 with the corrugations extending lengthwise of the cigar, said corrugations affording longitudinal air passages.

3. The improved cigar comprising a filler composed of a corrugated sheet of compressed tobacco rolled upon itself and a wrapper, one projecting edge of which is folded over the inner edge of the filler and the other edge of which serves to secure the 50 rolled filler in place. 55

4. The improved process of making a cigar which consists in superposing a plurality of sheets of moist tobacco, subjecting the same to pressure in a mold to compress the tobacco, and to form longitudinal corrugations therein, and then rolling the same 60 upon itself to form the cigar. 65

In testimony whereof I affix my signature, in presence of two witnesses.

FRANKLIN S. COOLEY.
